UNITED STATES PATENT OFFICE.

ELMER O. BEARDSLEY, OF CHICAGO, AND WALTER F. PIPER, OF OAK PARK, ILLINOIS,
ASSIGNORS TO THE BEARDSLEY & PIPER COMPANY, OF CHICAGO, ILLINOIS, A COR-
PORATION OF ILLINOIS.

MOLDING MACHINE.

Application filed July 18, 1921. Serial No. 485,506.

To all whom it may concern:

Be it known that we, ELMER O. BEARDSLEY and WALTER F. PIPER, both citizens of the United States, and residents of Chicago, in the county of Cook and State of Illinois, and Oak Park, in the county of Cook and State of Illinois, respectively, have invented certain new and useful Improvements in Molding Machines, of which the following is a full, clear, and exact description.

The invention relates to molding machines. One object of the present invention is to provide an improved portable molding machine which is mounted on a truck and adapted to be propelled over a floor on which the sand to be used is piled and which makes provision for the elevation of the sand and its delivery into a reservoir on the truck from which it can be readily shovelled into one of the molding machines on the truck, so that a working supply of sand will always be available to and within easy reach of the molder, so he can quickly and easily fill the flasks.

The invention consists in the several novel features hereinafter set forth and more particularly defined by claims at the conclusion hereof.

In the drawings: Fig. 1 is a perspective of a machine embodying the invention. Fig. 2 is a horizontal section. Fig. 3 is a side elevation of a portion of the machine. Fig. 4 is a vertical section.

The invention is exemplified in a machine comprising a portable truck adapted to be propelled over the floor of the molding room on which the sand is arranged in a pile or wind-row. Each truck comprises a frame built up of sides 5 and tubular cross-members 6 and 7 which are secured to the frame-sides in suitable manner to form a rigid frame. The truck is movably sustained by rear carrying wheels 8 which are cross-connected by a shaft 9 extending through the tubular member 7 and a pair of front carrying wheels 10 suitably journaled on the frame-sides 5. A supporting base 12 is rigidly secured to the tubular frame-members 6 and 7 by U-bolts 13, and is adapted to support on one side a molding machine 15 of the hand-squeezing type of usual construction and at its other side a molding machine 14 of the jarring type.

The machine comprises mechanism for conveying and elevating sand from the floor

in front of the machine to a receptacle on the truck for use in the molding machines. A cross-shaft 16 is journaled in the frame-sides 5 and is provided with spiral conveyor blades 17 and 18 which are adapted to disintegrate the sand on the floor and convey it to a central elevator which comprises an endless chain 19 and buckets 20 which are adapted to scoop up the sand fed thereto by the conveyors 17 and 18 and to discharge it, when elevated, into a chute 21 which delivers the sand into a receptacle 22 which serves as a reservoir for a supply of sand which is always available for molders at the molding machines. The lower portion of the chain 19 passes around a sprocket 25 on conveyor shaft 16 and its upper end passes around a sprocket 25' on a shaft 26 mounted in bearings 27 on a hollow standard 28 which is secured to the base 12. A discharge opening 23 is formed in the lower portion of the reservoir 22 through which the sand will fall into a platform 24 which is conveniently located between the molding machines and at such an elevation that the molder can easily and with facility shovel the sand from the platform 24 into the flasks on the molding machines located at the sides thereof. In discharging the sand from the buckets 20, it will be further disintegrated so that the reservoir 22 will contain a supply of sand which is in condition to be placed into the flasks. An electric-motor 29 supported on the truck drives the sand-conveying and elevating mechanism through a pinion 40 on the motor-shaft, an idler 41 meshing with said pinion and a gear 42 fixed to said idler and meshing with a gear 43 fixed to one end of the conveyor-shaft 16.

In order to keep the cross-conveyors supplied with sand, it is necessary to propel the truck over the foundry floor on which the sand is piled and, for this purpose, the truck-wheels 8 have toothed peripheries 33 which mesh with stationary toothed tracks 34 laid in the floor and said wheels are driven by power derived from the shaft 16. A crank-pin 35 is secured to one end of shaft 16 and reciprocates a pawl 37 which is adapted to step up a ratchet-wheel 38. A toothed pinion 39 is fixed to rotate with said ratchet-wheel and is formed with teeth which conform to and mesh with the teeth 33 of one of the traction-wheels 8.

A dog 39' engages the ratchet 38 to hold it against retraction. While the screw-conveyors on shaft 16 are operated, the wrist-pin 35 will step up the ratchet 38 to slowly 5 operate the wheels 8 and cause them to propel the truck over the molding room floor. This travel of the truck will cause the cross-conveyors and elevator to be continually supplied with sand for delivery 10 into the reservoir 22 so that there will be a constant supply of sand available on the platform 24 from which the molder can readily shovel the sand into the flasks on either of the molding machines.

15 The invention exemplifies a portable molding machine which is equipped with mechanism for propelling it towards a pile of sand on the floor and which breaks up and elevates the sand and delivers it into a reservoir 20 on the truck. A constant supply of sand is thus maintained on the platform 24 from which the sand can be easily and quickly shovelled into the flasks in the molding machine or machines on the truck.

25 The invention is not to be understood as restricted to the details set forth, since these may be modified within the scope of the appended claims, without departing from the spirit and scope of the invention.

30 Having thus described the invention, what we claim as new and desire to secure by Letters Patent, is:

1. In a molding apparatus, the combination of a portable truck adapted to travel on 35 a molding machine floor, means for propelling the truck, a molding machine mounted on the truck, a reservoir for a working supply of sand fixed on the truck and located relatively to said machine so sand may be 40 conveniently shovelled therefrom into a flask on or in the molding machine, and mechanism for conveying sand from a pile on the floor and delivering it into the reservoir.

2. In a molding apparatus, the combination of a portable truck adapted to travel on 45 a molding machine floor, means on the truck for propelling the truck, a molding machine mounted on the truck, a reservoir for a working supply of sand fixed on the truck and located relatively to said machine so 50 that sand may be conveniently shovelled therefrom into a flask on the molding machine, and mechanism for conveying sand from a pile on the floor and delivering it into the reservoir comprising an elevator mounted 55 to operate between the sides of the truck.

3. In a molding apparatus, the combination of a portable truck adapted to travel on a molding machine floor, means for propelling the truck, a molding machine mounted 60 on the truck, a reservoir for a working supply of sand fixed on the truck, a platform stationary on the truck onto which the sand falls from said receptacle, and from which sand may be conveniently shovelled into a 65 flask on or in the molding machine, and mechanism for conveying sand from a pile on the floor and delivering it into the reservoir.

4. In a molding apparatus, the combination of a portable truck adapted to travel on a molding machine floor, means for propelling the truck, a molding machine mounted on the truck, a reservoir for a working supply of sand fixed on the truck, a platform on 70 the truck onto which sand will fall from the receptacle and located so that sand may be conveniently shovelled therefrom into a flask on or in the molding machine, a cross-conveyor for sand on the floor of the molding 75 room, and an elevator centrally disposed on the truck for delivering sand from the conveyor into the reservoir to keep the platform supplied with sand.

ELMER O. BEARDSLEY.
WALTER F. PIPER.
